UNITED STATES PATENT OFFICE

132,745

DESIGN FOR A TEXTILE FABRIC OR SIMILAR ARTICLE

Charles Rosenstein, Paterson, N. J.

Application May 16, 1942, Serial No. 106,917

Term of patent 3½ years

To all whom it may concern:

Be it known that I, Charles Rosenstein, a citizen of the United States, residing in Paterson, county of Passaic, and State of New Jersey, have invented a new, original, and ornamental Design for a Textile Fabric or Similar Article, of which the following is a specification, reference being had to the accompanying drawing, forming part thereof.

The figure of the drawing is a plan view of a textile fabric showing my new design.

I claim:

The ornamental design for a textile fabric or similar article, as shown.

CHARLES ROSENSTEIN.
